UNITED STATES PATENT OFFICE.

JOHN L. SEAGONDOLLAR AND WILLIAM A. WINANS, OF HOISINGTON, KANSAS.

HYDROCARBON-BURNER.

No. 867,425.

Specification of Letters Patent.

Patented Oct. 1, 1907.

Application filed April 12, 1907. Serial No. 867,816.

To all whom it may concern:

Be it known that we, JOHN L. SEAGONDOLLAR and WILLIAM A. WINANS, citizens of the United States, residing at Hoisington, in the county of Barton and 5 State of Kansas, have invented new and useful Improvements in Hydrocarbon-Burners, of which the following is a specification.

This invention relates to hydrocarbon burners; and the object thereof is to provide, in a manner as herein- 10 after set forth, a burner of such class with means which will insure perfect combustion with the smallest possible amount of residuum.

A further object of the invention is to provide the burner with means for retarding the flow of hydrocarbon over the distributing member therefor, thereby 15 facilitating the vaporizing of the hydrocarbon.

Further objects of the invention are to provide a hydrocarbon burner which shall be simple in its construction, strong, durable, readily cleaned, efficient 20 in its use, readily set up and comparatively inexpensive to manufacture.

With the foregoing and other objects in view the invention consists in the novel construction, combination and arrangement of parts hereinafter more 25 specifically described and illustrated in the accompanying drawings, wherein is shown the preferred embodiment of the invention, but it is to be understood that changes, modifications and variations can be resorted to which come within the scope of the 30 claims hereunto appended.

In describing the invention in detail reference is had to the accompanying drawings wherein like characters refer to corresponding parts throughout the several views and in which—

35 Figure 1 is a transverse section of a hydrocarbon burner in accordance with this invention positioned within a stove, Fig. 2 is a perspective view of the cap plate. Fig. 3 is a like view of the distributing plate, and, Fig. 4 is a similar view of the receiving tray and 40 its supports.

In the drawings is shown by way of example the adaptation of the invention in connection with a rectangular fire box, but it is obvious that the elements of the burner can be so modified as to enable the 45 burner to be used in connection with a circular fire box.

Referring to the drawings by reference characters, 1 denotes a fire box of a stove within which is mounted a burner in accordance with this invention. The 50 burner can be supported in any suitable manner preferably mounted upon the grate bars.

The burner comprises a pair of supporting members 2, 3 with each of the top edges thereof formed with a shoulder 4. The portion 5 of the top edge of each of 55 the members 2, 3 is of concave curvature, while the

portion 6 is of convex curvature. Between the members 2 and 3 is positioned a receiving tray 7 substantially concave in contour and the said tray 7 is connected or formed integral with the members 2, 3. The rear edge 8 of the tray 7 is positioned below the 60 top edge of the members 2, 3 at the rear thereof.

Formed integral with the lower face of the tray 7 and projecting rearwardly is an arm 9 having an elongated slot 10 through which extends an oil supply pipe 11, the latter communicating with a suitable reservoir (not shown). Means may also be provided for regulating the supply of oil from the reservoir, such means being of any suitable construction and not shown. The supply pipe 11 also extends through a rearwardly-projecting apertured lug 12 formed integral with the edge 8 of the tray 7 and arranged in alinement with the arm 9. Arranged above the edge 8 of the tray 7 and of such width as to project over, as well as rearwardly of the tray, is an oil-distributing plate 13, which has its lower face formed with a boss 75 14. The boss 14 is mounted upon the lug 12 so that in connection therewith the plate 13 will be positioned at a point removed from the top edge 8 of the tray 7 thereby forming an air inlet passage which communicates at one end with the air chamber 15 and at its 80 other end opens into the tray 7. The forward portion of the plate 13 slopes downwardly towards the tray 7. The upper face of the plate 13 is cut away so that the forward portion thereof will be formed in a sloping manner as at 16 and the rear portion recessed so as to 85 form an oil-receiving chamber 17, with which the pipe 11 communicates the latter extending up through the boss 14 and through the plate 13. The cutting away of the upper face of the plate 13 forms a pair of end walls 18 the top edge of which is above the plane 90 of the portion 16 so as to prevent the oil from flowing off the ends of the plate 13. The oil-receiving chamber 17 retards the distribution of the oil through the medium of the plate 13 so that it will become heated owing to the arrangement of the elements of the 95 burner as shown, and consequently facilitate the vaporizing of the oil.

Arranged over the distributing plate 13 is a cap 19 of convex curvature and which is of greater width than the plate 13 and so constructed as to overlap the plate 100 13 at the front and rear thereof and in this connection it will be stated that the rear of the cap 19 is formed with a depending flange 20 adapted to abut against the fire back 21 and the front of the cap slopes downwardly 105 in such a manner as to extend to a point slightly below the forward end of the plate 13 as at 22. Between the rear of the plate 13 and the flange 20 an air inlet 23 is formed which communicates with the air chamber 15 and the vaporizing chamber 24 which is formed between the cap 19 and the plate 13. The cap 19 is 110

formed with a pair of laterally-extending offsets 25 adapted to seat upon the portion 6 of the top edge of the members 2, 3 so as to support the cap above the plate 13. The forward ends of the offsets 25 abut 5 against the shoulders 4 and the top edges of the offsets 25 are so shaped as to form a continuation of the edge 5 of the members 2, 3.

In the operation of the invention it will be seen that the oil passes upward through the supply pipe 11 and, 10 owing to the arrangement of such pipe in the air chamber 15 the oil as it travels through the pipe will not be heated to any great extent. The oil is discharged from the pipe 11 into the chamber 17 and as the oil overflows it will travel in a thin film downwardly over the surface 15 of the plate 13. The plate 13 is heated by the flame at its lower portion so that the oil is partially vaporized and the gas formed in the chamber between the plate and cap passes downward and escapes at the lower portions thereof, where it is ignited. Certain 20 portions of the oil do not readily vaporize under the heat here present. They fall over the forward end of the plate 13 in a thin film or layer through which the current of air supplied through the passage formed between the tray and plate is passed at the point of ignition, and, owing to the supply of air it will cause combustion so that not only will the gas be consumed but the oil which passes over the plate 13. Any residuum falls into the tray 7. The tray 7 also acts as a means to receive the small quantity of oil for the initial starting 25 when kindling a fire. The plate 13 at the forward end thereof is the hottest and as the cap also gets very hot, a large proportion of the crude oil is vaporized which, united with the air at the forward end of the plate, burns with a clear white flame and intense heat with a 30 very small consumption of oil and a minimum quantity of soot, smoke or residuum. The regulation of the flame can be had by increasing or decreasing the supply of oil as occasion requires.

From the construction of a hydrocarbon burner in a 40 manner as stated it is evident that a great increase in cleanliness of operation, represented by the practical elimination of soot and smoke, is obtained, which is evident owing to the vaporizing of the oil before combustion. The smoke and soot produced by the small 45 amount of oil passed over the plate 13 without vaporizing is burned in the receiving tray and furthermore is

practically consumed in the intense heat of the gas flame.

The removability of the cap enables the various elements to be readily cleaned as will be evident.

What we claim is—

1. A hydrocarbon burner comprising a receiving tray provided with a lug and an arm, a discharging plate mounted over the top of the tray and having its upper face formed with a sloping portion and a depression and its lower face provided with a boss, said depression forming an oil receiving chamber, said boss adapted to be seated upon said lug for positioning the plate above the tray forming thereby an air passage between the plate and the tray and which opens into the tray, an oil supply pipe extending through said lug, arm and boss and communicating with said depression, and a cap inclosing the plate and suitably spaced therefrom to form an air passage, said cap conforming in contour to the shape of the plate. 55

2. A hydrocarbon burner comprising a pair of supporting members, a concavo-convex tray formed on the inner face of said members and provided with a rearwardly-extending apertured arm and a rearwardly-extending apertured lug, a supply pipe extending through the arm and the lug, a discharging plate secured to the supply pipe arranged above the rear edge of said tray forming thereby an air channel opening into the tray, said cap having a portion of its upper face sloping and its remaining portion depressed to form the oil-receiving chamber communicating with the supply pipe, and a cap inclosing said plate and 70 projecting into said tray and suitably spaced from the plate forming thereby an air inlet passage and a vaporizing chamber. 75

3. A hydrocarbon burner comprising a pair of supporting members, a receiving tray substantially concave in 80 contour formed on the inner face of said members, a rearwardly-extending apertured lug formed integral with the top edge of the rear of said tray, a distributing plate mounted upon said lug forming thereby an air channel 85 between the plate and the rear edge of the tray, said plate having a portion of its upper face depressed to form an oil-receiving chamber communicating with an oil supply and the remaining portion of said face sloping downwardly towards the tray, said plate having a wall at each end extending above the sloping portion of its upper face, and a cap mounted upon said members and inclosing said plate, said cap spaced from the plate forming thereby an air inlet passage and a vaporizing chamber. 90

In testimony whereof we have hereunto set our hands in presence of two subscribing witnesses.
